UNITED STATES PATENT OFFICE.

HARRY A. YEIDER, OF GRAND RAPIDS, MICHIGAN.

COFFIN-HOLDING DEVICE FOR HEARSE.

1,274,835.

Specification of Letters Patent. Patented Aug. 6, 1918.

Application filed February 21, 1918. Serial No. 218,426.

To all whom it may concern:

Be it known that I, HARRY A. YEIDER, a citizen of the United States, residing at Grand Rapids, in the county of Kent and 5 State of Michigan, have invented new and useful Improvements in Coffin-Holding Devices for Hearses, of which the following is a specification:

The present invention relates to coffin-10 holding devices for hearses; and its object is, generally, to provide an improved device for holding against movement the coffin carried by the hearse; and further, to provide such a device whereby the coffin may be 15 yieldedly held; and further, to provide such a device whereby the coffin may be securely held although not in the center of the hearse; and further, to provide such a device whereby the holding members may be 20 released by the opening of the hearse's door; and further, to provide such a device whereby said members may be held in released position by swinging the door to its open position.

25 This object is attained by, and the invention finds preferable embodiment in, the structure hereinafter particularly described and illustrated by the accompanying drawings, in which:

30 Figure 1 is a horizontal section of a hearse, showing a plan of its floor and a coffin resting thereon, part of the coffin and of the floor beneath it being broken away to show the parts beneath the floor; and

35 Fig. 2 is an enlarged detail view of a coffin-holding member and connected parts.

The coffin-holding members, 1, 2, 3, 4 are movable toward and away from each other, as in the slide bearings 5 respectively, cut 40 through the floor 6 of the hearse. A pair 1, 3 of these members are desirably provided for holding engagement with one side of the coffin 7, and another pair, 2, 4 for such engagement with the coffin's other side. These 45 members are yieldedly pressed into such engagement with the coffin by springs 8 connected at one end to said members respectively and at the other end preferably to a central fixed anchorage 9. The holding

50 members are drawn against the pressure of the springs by flexible means, as the cords 10, connected to the members 1, 2 respectively and passing around pulleys 11, and cords 12 connected to the members 3, 4 respectively. These cords are connected to a pivoted arm, as the hinged doors 13, 14, so

that when the doors are swung to open position, (as is door 14) the cords are drawn and the holding members are moved (as are the members 2, 4) to release the coffin. When 60 the doors are closed, as is door 13, the cords swing inwardly and the pressure of the springs tends to retain the doors in closed position; but when the doors are opened, as is door 14, the cords swing outwardly to the 65 other side of the axis of the door's hinge 15, so that the holding members are securely held from engagement with the coffin and the springs tend to retain the doors in open position.

70 It will be seen that the coffin is yieldedly held by the holding members and that although the coffin may be placed to one side or the other of the longitudinal center line of the hearse, the coffin will nevertheless be 75 held by the holding members on both sides, and without being pushed to one side or the other by the holders which are nearer the coffin on either side. The several springs may be regarded as one spring having divergent branches, for their operation is to draw 80 all the holding members toward each other, and the anchorage 9 may be dispensed with.

The invention being intended to be 85 pointed out by the claims severally, is not to be limited to or by details of construction shown or described.

I claim:

1. In a hearse; a plurality of coffin-holding members movable toward and away 90 from each other; a spring pressing said members toward each other; means connected to said members and adapted to move them away from each other.

2. In a hearse; a pivoted arm; a plurality 95 of coffin-holding members movable toward and away from each other; a spring pressing said members toward each other; means connected to said members and to the arm and adapted to move said members away 100 from each other by the arm's turning movement.

3. In a hearse; a pivoted arm; a plurality 105 of coffin-holding members movable toward and away from each other; a spring pressing said members toward each other; means connected to said members and to the arm and adapted to move said members away from each other by the arm's turning movement and adapted to be swung by the arm's 110 said movement to one side of the arm's pivot in one position of the arm and to the

other side of said pivot in another position of the arm.

4. In a hearse; a hinged door; a plurality of slide bearings; coffin-holding members 5 slideable in said bearings toward and away from each other; springs pressing said members toward each other; flexible means connected to said members and to the door and adapted to move said members away from each other by the door's opening 10 movement.

5. In a hearse; a hinged door; a plurality of slide bearings; coffin-holding members 15 slideable in said bearings toward and away

from each other; springs pressing said members toward each other; flexible means connected to said members and to the door and adapted to move said members away from each other by the door's opening movement and adapted to be swung by the door's 20 movement to one side of its hinge in the open position of the door and to the other side of said hinge in the door's closed position.

In testimony whereof I have hereunto set 25 my hand at Grand Rapids, Michigan, this 6th day of February, 1918.

HARRY A. YEIDER.
